(57) **CLAIM**

The ornamental designs for a chair, as shown and described.

DESCRIPTION

FIG. 1 is a rear perspective view of a chair, with an outboard motor shown in dashed lines and which outboard motor does not form a part of the claimed design;

FIG. 2 is a front view of the chair, with an outboard motor shown in dashed lines and which outboard motor does not form a part of the claimed design;

FIG. 3 is a rear view of the chair, with an outboard motor shown in dashed lines and which outboard motor does not form a part of the claimed design;

FIG. 4 is a left side view of the chair, with an outboard motor shown in dashed lines and which outboard motor does not form a part of the claimed design;

FIG. 5 is a right side view of the chair, with an outboard motor shown in dashed lines and which outboard motor does not form a part of the claimed design;

FIG. 6 is a top view of the chair;

FIG. 7 is a bottom view of the chair, with a throttle handle shown in dashed lines and which throttle handle does not form a part of the claimed design;

FIG. 8 is a rear perspective view of a second embodiment of a chair, with a portion of an outboard motor shown in dashed lines and which portion xof an outboard motor does not form a part of the claimed design;

FIG. 9 is a front elevation view of the chair, with a portion of the outboard motor shown in dashed lines and which portion of the outboard motor does not form any part of the claimed design;

FIG. 10 is a rear elevation view of the chair, with a portion of the outboard motor shown in dashed lines and which portion of the outboard motor does not form any part of the claimed design;

FIG. 11 is a right side elevation view of the chair, with a portion of the outboard motor shown in dashed lines and which portion of the outboard motor does not form any part of the claimed design;

FIG. 12 is a left side elevation view of the chair, with a portion of the outboard motor shown in dashed lines and which portion of the outboard motor does not form any part of the claimed design;

FIG. 13 is a top plan view of the chair;

FIG. 14 is a bottom plan view of the chair, with a portion of the outboard motor shown in dashed lines and which portion of the outboard motor does not form any part of the claimed design;

FIG. 15 is a front elevation view of a third embodiment of a chair, with a portion of the outboard motor shown in dashed lines and which portion of the outboard motor does not form any part of the claimed design;

FIG. 16 is a rear elevation view of the chair, with a portion of the outboard motor shown in dashed lines and which portion of the outboard motor does not form any part of the claimed design;

FIG. 17 is a right side elevation view of the chair, with a portion of the outboard motor shown in dashed lines and which portion of the outboard motor does not form any part of the claimed design;

FIG. 18 is a left side elevation view of the chair, with a portion of the outboard motor shown in dashed lines and which portion of the outboard motor does not form any part of the claimed design;

FIG. 19 is a top plan view of the chair; and,

FIG. 20 is a bottom plan view of the chair, with a portion of the outboard motor shown in dashed lines and which portion of the outboard motor does not form any part of the claimed design.

The drawing disclosure of this application includes broken line depictions of an outboard motor of a chair, which outboard motor does not form a part of the claimed design.
